UNITED STATES PATENT OFFICE.

WILLIAM H. MUZZY, OF DAYTON, OHIO, ASSIGNOR TO NATIONAL CASH REGISTER COMPANY, OF JERSEY CITY, NEW JERSEY, A CORPORATION OF NEW JERSEY.

CASH-REGISTER.

SPECIFICATION forming part of Letters Patent No. 773,091, dated October 25, 1904.

Application filed April 9, 1904. Serial No. 202,460. (No model.)

To all whom it may concern:

Be it known that I, WILLIAM H. MUZZY, a citizen of the United States, residing at Dayton, in the county of Montgomery and State 5 of Ohio, have invented certain new and useful Improvements in Cash-Registers, of which I declare the following to be a full, clear, and exact description.

This invention relates to improvements in 10 cash-registers, and has more particular relation to improvements in registers of the multiple-drawer type.

One of the several objects of the invention is to provide a cash-register with improved 15 multiple-drawer devices which are not dependent for operation upon the regular operation of the register proper.

Another object of the invention is to provide improved indicating devices for the respective cash-drawers and also for the clerks' or department selecting devices.

A further object is to provide improved keys or controlling devices for the clerks' selecting mechanism and the cash-drawer-releasing devices.

With these and incidental objects in view the invention consists in certain novel features of construction and combinations of parts, the essential elements of which are set forth in 30 appended claims and a preferred form of embodiment of which is hereinafter specifically described with reference to the drawings which accompany and form part of this specification.

35 Of said drawings, Figure 1 represents a transverse vertical section through a machine of the type patented to H. S. Hallwood by English Patent No. 4,543 of 1903, with the present improvements applied thereto, parts 40 of the machine being omitted for clearness. Fig. 2 represents a detail side elevation of the special key-bank and the special indicator and its connections. Fig. 3 represents a front elevation, partly in section, of the devices shown 45 in Fig. 2. Fig. 4 represents a detail rear elevation of the drawer-key switches, and Fig. 5 represents a detail side elevation of the special combination-indicator.

Described in general terms, the machine to which the present improvements have been applied may be said to comprise a series of operating-yokes 2, mounted upon a main shaft 1, and each provided with a step-frame 3, which co-operates with the ends of the key-shanks to limit the movement of the yokes 2 according to 50 the value of the key operated. After the yokes 2 have been released and allowed to descend to positions determined by the previously-operated keys they are returned to their normal 55 positions to effect the registration by an operating-handle 4, which is connected to the main operating-lever 5, journaled on the shaft 1 and arranged to contact with and elevate all of said yokes 2.

As the devices for the clerks' key-bank are 60 the only ones illustrated in the present drawings, the description will be confined to this particular bank; but it will be readily understood that the regular banks of amount-keys and their connections are controlled and operated in a manner well known in the art and 65 shown and described in the aforesaid patent to Henry S. Hallwood.

The yoke 2 of the special clerks' key-bank is provided with a lip 6, through which passes 70 an adjusting-bolt 7 to engage with the rear end of a lever 8, mounted on the shaft 1, as plainly shown in Fig. 2. The forward end of the lever 8 is connected to its respective step-segment 3 by a coil-spring 9, whereby the 75 rear end of the lever is normally held in contact with the bolt 7 as the yoke 2 descends. The forward end of the lever 8 is connected to a rack-bar 10, which meshes with a pinion 11, fast to the special clerks' indicator 12, 80 which is journaled upon a transverse shaft 13, as also shown in Fig. 3. By this means the movements of the yoke 2 are communicated to the indicator 12 and the same is moved to a position to indicate a character correspond- 85 ing to the character upon the special clerks' key 14 which has been depressed. Beside each key 14 is a special drawer-key 15, the 90 two keys together forming a single key in appearance, but as a matter of fact being alto- 95 gether independent of each other in construc-

tion and operation. The shanks 16 and 17 of the keys 14 and 15 lie side by side and operate through the spaced guide-plates 18 and 19 of the main frame in pairs, each pair forming 5 in appearance a single key-shank and being surrounded by a coil-spring 20, which engages pins 21 and 22 in the respective shanks to return the keys to their normal positions after being depressed. The pins 21 of the keys 14 are 10 arranged to coöperate with hooks 23, formed on a detent-plate 24, which is journaled upon the shaft 1, to lock the keys 14 in their depressed positions in a manner well known in the art and shown and described in the aforesaid 15 patent.

The detent-plate 24 is normally held in its elevated position by a pin 25, mounted thereon and resting upon a shoulder 26, formed on a pivoted lever 27, which is journaled upon a 20 transverse shaft 28 and projects to the rear of all of the key-pins 21. The plate 27 is normally drawn forward by a coil-spring 29, which connects it to the main frame. When one of the keys 14 is depressed, its pin 21 contacts with the forward edge of the plate 27 25 and forces said plate rearward to move the shoulder 26 from under the pin 25 and allow the detent 24 to drop and latch the key in its depressed position. The detent 24 is subsequently operated to release the key 14 through 30 a pendent arm 30, formed on said detent, and which is engaged and elevated by a bar 31, connected to a lever 32, which is mounted upon a transverse shaft 33, and is provided 35 near its rear end with a pivoted pawl 34, having an angular flange 35. This pawl is normally drawn into the position shown in Fig. 1 by a coil-spring 36, which connects it to the lever 32, a stop 37 limiting the movement of 40 the pawl. The lever 5 carries an antifriction-roller 38, which when said lever descends engages the under side of the flange 35 and rocks the pawl 34 upon its pivot. As the lever 5 is returning toward its normal position the 45 roller 38 engages the upper side of the flange 35, and as the pawl 34 again rocks in the opposite direction the rear end of the lever 32 is depressed and the detent 24 thus elevated to release the depressed key.

50 It will be seen from the foregoing description that any one of the keys 14 may be depressed and latched in its depressed position without in any wise interfering with or operating the companion drawer-key 15, or the 55 key 15 may be independently operated to release the desired cash-drawer. In ordinary operation, however, the companion keys 14 and 15 are depressed together by a single operation. In such operation the operator 60 places his finger over both keys 14 and 15 and depresses the same simultaneously. This operation, as before explained, causes the key 14 to become latched in its depressed position to control the subsequent movement of the 65 indicator 12. The depression of any key 15,

however, effects the immediate release of its respective cash-drawer. The cash-drawers 40 are mounted in a casing or cabinet 41 in any suitable manner, so that they may be readily ejected by springs 42 when released. Each 70 of these drawers is provided upon its rear wall with a beveled latch-bracket 43, which is arranged to engage the vertically-movable latch-plunger 44, suitably guided in the main frame and cabinet. The upper end of each 75 plunger 44 is formed with an enlarged aperture 45, into which projects the pins 46. These pins 46 are mounted upon a series of levers 47, which are journaled upon the shaft 33, and are provided at their forward ends 80 with antifriction-rollers 48, as more clearly shown in Fig. 1. Each of these rollers 48 is engaged by the cam end of an arm 49, these arms being pendent from the right-hand ends 85 of a series of nested sleeves 50, which are supported upon a transverse shaft 51 and are provided at their opposite ends with a series of curved arms 52, which are arranged to coöperate with the key-pins 22, as plainly shown in Figs. 1 and 3. The arms 52 are of varying 90 lengths and are so arranged that each arm will coöperate with only one of the pins 22, so that when one of the keys 15 is depressed its particular lever 52 will be rocked and by the forward movement of its cam-arm 49 will 95 elevate the rear ends of its lever 47 against the tension of a spring 53, which connects it to the main frame, and thus unlatch its respective cash-drawer. By this means the operator, if he so desires, may open any particular 100 cash-drawer by simply depressing the key 15 pertaining thereto, this operation having no effect whatever upon the machine proper.

Extending across all of the levers 47 is a pivoted yoke 54, mounted upon the shaft 33 105 and provided at its rear with a pawl 55, which is limited in its movements in one direction by a stop-pin 56. This pawl 55 coöperates with a pin 57, mounted upon a spring-pressed latch-frame 58, which is journaled upon a 110 transverse rod 59 and is formed with a latch-nose 60. A series of spring-pressed plungers 61 are mounted in an insulating cross-bar 63 in such manner as to be elevated by the rear 115 ends of the levers 47 when the latter are operated to release the cash-drawers. Each of the plungers 61 is connected by a wire 64 to one of a series of incandescent lamps 65, hereinafter more particularly described. A series of spring-pressed contact-plungers 66 are 120 mounted in a metallic plate 67, which plate is connected to a main circuit-wire 69, which is connected to all of the lamps 65. Each of the plungers 61 is provided with a head 70, which when a plunger is elevated passes above the 125 pivoted frame 58, so that the latter will support the plunger in contact with the confronting contact-plunger 66 when the lever 47 returns. When another lever 47 is operated, the previously-elevated plunger 61 is released 130

and the new plunger latched in its elevated position. Any lamp 65 that is illuminated thus remains illuminated until the subsequent operation of some one of the keys 15.

5 As best shown in Fig. 3, the lamps 65 are arranged within a circular casing 72, which is mounted rigidly upon the top of the cash-register casing, as shown in Fig. 5. This casing is formed upon each side with a circular opening 73, within which operate metallic disks 74, said disks being carried by a hub 75, which is journaled in pendent arms 76, secured to the casing 72. The hub 75 carries a pinion 77, which meshes with a gear 15 78; which gear in turn meshes with the pinion 11 of the special indicator. The gear 78 is suitably journaled in the frame 72 and is cut away, as shown at 79, to prevent the obstruction of any of the lamps 65. Each of the 20 disks 74 is provided with ten apertures, nine of which are designated 78^a and the remaining one 79^a. The aperture 79^a of each disk is covered by a plain white glass, while the apertures 78^a of each disk are covered by red 25 or other colored glass.

It will be seen from the above description that when the special indicator 12 is rotated the disks 74 will be correspondingly positioned. This movement of the disks 74 brings 30 the apertures 79^a opposite the lamp 65, which is connected to the cash-drawer pertaining to the particular clerk who has operated the machine. If this clerk has properly operated his drawer-key 15, the particular lamp opposite 35 the apertures 79^a will be illuminated and a white light will be shown from both sides of the machine. This white light will be an indication to the clerks and proprietor that the machine has been properly operated and 40 that a cash-drawer has been opened corresponding to the clerks' key 14 which has been depressed. Should a clerk, however, after pressing his particular clerk's key 14 open the cash-drawer of another clerk, a lamp 45 would be illuminated opposite one of the apertures 78^a and a red light would thus be shown, which would indicate to the clerks and proprietor that the machine was being improperly manipulated. If so desired, the 50 aperture 78^a may be altogether omitted, and the absence of any light at all when the machine is operated would convey the same information as the red light described above. As the red and white signals are so well understood by every one, I prefer to employ 55 disks 74, having ten apertures, as described, with the red and white glasses or other transparent material.

The casing 72 is preferably arranged upon 60 the cabinet so that the light will be visible to each side of the machine rather than to the back and front of the machine, whereby the clerks may discern the colors of the signals displayed even when they are at a great distance 65 from the machine. It will of course

be understood that the indicator 12 when set is held in its set position by any suitable detent means, but as such means forms no part of the present invention it has not been illustrated. Such holding devices, however, are 70 fully described and shown in the aforesaid patent to Hallwood.

In order to prevent the possibility of the light from one lamp illuminating an aperture 78^a or 79^a adjacent thereto, I prefer to provide 75 radial partitions 80 in the casing 72 between the respective lamps. As the customers or purchasers may also be interested in the meaning of the special light-indicator, I have provided the casing 72 with a series of characters 80 located adjacent to the respective lamps 65. The illumination of any aperture 79^a or 78^a in proximity to any one of these characters will form an indication of which cash-drawer 85 was opened for the preceding operation. 90 The clerks will also become accustomed to the location of the different lights about the circular casing 72 and will be able to ascertain at a distance just what cash-drawer has been opened. This will prevent one clerk 95 operating the clerk's key and opening the cash-drawer of a companion clerk when the latter clerk is far enough away from the machine to be out of hearing of the special alarms, which are applied to the cash-drawers 95 in the usual manner to inform the listener by audible signal as to which cash-drawer is being opened.

While the form of mechanism here shown and described is admirably adapted to fulfil 100 the objects primarily stated, it is to be understood that the invention is not confined to any form of embodiment of the invention here disclosed, for it is susceptible of embodiment in various forms all coming within the scope 105 of the claims which follow.

Having thus described the invention, what is claimed as new, and desired to be secured by Letters Patent, is—

1. In a cash-register, the combination with 110 an operating mechanism, of a series of clerks' setting elements, a special signaling device controlled thereby, a series of cash-receptacles, means controlling said receptacles, and special drawer-signaling devices governed by 115 the drawer-controlling means whereby the two signaling devices coact to produce a single intelligible signal.

2. In a cash-register, the combination with 120 an operating mechanism, of a plurality of cash-receptacles, clerks' controlling elements, and independent signals representing the cash-receptacles and the clerks' controlling elements, and coacting to produce a single intelligible signal. 125

3. In a cash-register, the combination with 130 an operating mechanism, of clerks' controlling mechanism, a series of cash-receptacles, and independent signals representing the clerks' selecting mechanism and the cash-receptacles,

and coacting in such manner as to produce a single intelligible signal.

4. In a cash-register, the combination with an operating mechanism, of a series of clerks' keys, a series of cash-receptacles, a series of keys controlling said receptacles, and independent signals for the clerks' keys and receptacles, coacting in such manner as to produce a single intelligible signal.

10 5. In a cash-register, the combination with an operating mechanism, of a series of clerks' keys, a series of cash-receptacles, a special indicator, a special signal connected to the indicator, and independent signals for the cash-receptacles; said signals coacting to produce a single intelligible signal.

20 6. In a cash-register, the combination with an operating mechanism, of a series of clerks' keys, a special indicator controlled by the same, a rotary signal connected to said indicator, a series of cash-receptacles, and independent signals representing said receptacles; said signals coacting to produce a single intelligible signal.

25 7. In a cash-register, the combination with an operating mechanism, of a series of clerks' keys, a series of cash-receptacles, and a series of receptacle-keys located immediately adjoining the corresponding clerks' keys whereby by a clerk's key and a receptacle-key corresponding thereto may be operated by the pressure of a single finger.

30 8. In a cash-register, the combination with an operating mechanism, of a series of clerks' keys, a series of cash-drawers, and a series of independent drawer-release keys located immediately adjoining the clerks' keys whereby corresponding clerks' and drawer keys may be simultaneously operated by one finger.

40 9. In a cash-register, the combination with an operating mechanism, of a series of cash-receptacles, apertured key-guides, and a series of controlling elements mounted in the respective apertures in said guides and each comprising a clerk's key and a drawer-release key sliding against the same, and guided by said clerk's key.

45 10. In a cash-register, the combination with an operating mechanism, of a clerk's controlling mechanism, a movable member formed with an aperture and connected to the controlling mechanism whereby the aperture may be positioned according to the operation of said controlling mechanism, a series of cash-receptacles, and signals representing said receptacles and located at the different points to which the aperture may be brought.

50 11. In a cash-register, the combination with an operating mechanism, of a clerk's selecting mechanism, a movable apertured member controlled by said selecting mechanism whereby the aperture may be brought to different positions, a series of cash-receptacles, and a series of signals representing said receptacles

and occupying the different positions to which the aperture may be brought.

55 12. In a cash-register, the combination with an operating mechanism, of a series of clerks' keys, an apertured disk controlled by said keys whereby the aperture may be brought to different positions, a series of cash-receptacles, means for opening said receptacles, a series of signals occupying the different positions to which the aperture of the disk may be brought, and means for bringing the signals into operation according to the cash-receptacle opened.

60 13. In a cash-register, the combination with an operating mechanism, of a series of clerks' keys, an apertured disk controlled by said keys, a series of cash-drawers, a series of signals, and means for bringing the signals into operation according to the cash-drawer opened.

65 14. In a cash-register, the combination with an operating mechanism, of a series of clerks' keys, an indicator controlled by said keys, a series of cash-drawers, a series of drawer-release keys, a rotary disk provided with signal-apertures and connected to the indicator, and a series of signals controlled by the drawer-release keys; the apertured disk and signals coacting to produce a single intelligible signal.

70 15. In a cash-register, the combination with an operating mechanism, of a series of clerks' keys, a series of drawer-keys, an indicator controlled by the clerks' keys, a series of cash-drawers released by the drawer-keys, and independent signals controlled by the drawer-keys and the indicator and coacting to produce a single intelligible signal.

75 16. In a cash-register, the combination with an operating mechanism, of a clerk's setting mechanism, a movable member controlled by the clerks' setting mechanism and formed with a series of apertures covered by transparent colored material, a series of cash-receptacles, a series of signals positioned back of the movable member, and means for bringing the signals into operation according to the cash-receptacle opened.

80 17. In a cash-register, the combination with an operating mechanism and connections, of a special rotary indicator, an apertured disk connected to said indicator, a series of lights occupying the different positions to which the aperture of said disk may be brought, a series of cash-receptacles, and means for bringing the lights into operation according to the cash-receptacle opened.

85 18. In a cash-register, the combination with an operating mechanism, of two spaced rotary disks connected thereto and formed with apertures, a series of cash-receptacles, and a series of lights located between the spaced disks and arranged to be thrown into operation according to the receptacle opened to display the signal from each side of the machine.

19. In a cash-register, the combination with an operating mechanism, of two spaced rotary disks connected thereto and each of the same formed with a series of apertures covered with 5 transparent colored material, lights located between said disks, a series of cash-receptacles, and means for bringing the lights into operation according to the receptacle opened whereby a colored signal is displayed at both 10 sides of the machine.

20. In a cash-register, the combination with an operating mechanism, of a series of clerks' keys, a signal-operating member controlled

by the same, a series of cash-drawers, drawer-release devices, a series of illuminated signals 15 controlled by the drawer-release devices, and means for retaining the illuminated signals in operation after one drawer-release device is actuated until another drawer-release is subsequently moved. 20

In testimony whereof I affix my signature in the presence of two witnesses.

WILLIAM H. MUZZY.
